W. D. COOLIDGE,
METHOD OF REMOVING GASES AND APPARATUS PRODUCED THEREBY,
APPLICATION FILED OCT. 6, 1916.
1,323,836. Patented Dec. 2, 1919.

His Attorney.

UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

METHOD OF REMOVING GASES AND APPARATUS PRODUCED THEREBY.

1,323,836.

Specification of Letters Patent.

Patented Dec. 2, 1919.

Application filed October 6, 1916. Serial No. 124,186.

To all whom it may concern:

Be it known that I, WILLIAM D. COOLIDGE, a citizen of the United States, residing at Schenectady, in the county of Schenectady, State of New York, have invented certain new and useful Improvements in the Methods of Removing Gases and Apparatus Produced Thereby, of which the following is a specification.

10 The present invention relates to the removal of gases other than the rare gases, from an inclosed space, and is applicable both to the production and maintenance of very high vacua, and to the purification of 15 the rare or noble gases, such as argon, neon, krypton or xenon.

The use of the metals calcium, magnesium, sodium and potassium has been suggested for the chemical removal of gases. However, the high vapor pressure of these metals 20 offers a serious drawback to their use for all purposes and particularly for certain types of electrical apparatus, having a very high vacuum.

25 I have discovered that the metals of the rare earth group, having a low vapor pressure, particularly thorium and zirconium, are peculiarly well suited for the removal of gases capable of chemical combination, such as oxygen, nitrogen, hydrogen, water vapor, the oxids of carbon and the like. These metals form by combination with these gases chemically stable compounds of low vapor pressure.

35 The accompanying drawings illustrate two forms of electrical devices to which my invention is applicable; Figure 1 showing an X-ray tube operating by pure electron conduction in a very high vacuum, and Fig. 40 2 a rectifier containing a filling of rare gas such as argon. Both devices are shown as provided with a quantity of finely divided rare earth metal.

The device shown in Fig. 1 comprises an 45 inclosing envelop 1, provided with a cathode 2, and an anode or target 3. The cathode consists of tungsten or other suitable refractory material, and is connected to leads 4, 5, sealed into the envelop and connected 50 to the members of a terminal 6, constructed similarly to an incandescent lamp base. The cathode is surrounded by a focusing ring 7, electrically connected to the cathode and supported by a stem 8, sealed into the glass 55 stem 9. The anode stem 10 is carried by

an iron or molybdenum tube 11 fitted within a glass sleeve 12. The anode lead 13 is likewise sealed into the envelop and connected to an external terminal 14.

60 Preferably the bulb is first evacuated in the usual way to vacuum high enough to enable a pure electron discharge to be passed without positive gas ionization, as described by me, for example, in the *Physical Review* for December, 1913. Dry air or nitrogen is 65 then admitted to the bulb and the thorium, zirconium or the like, preferably in a finely divided state, is introduced from a side tube, (as shown in connection with Fig. 2) or, by cutting the connection to the pump. The 70 connection to the pump is re-established if broken, and the bulb re-evacuated. Heat is then applied to the envelop wall adjacent to the metal powder 15, as by the use of an external gas flame, to start a reaction between 75 the metal and residual gas within the tube including gases absorbed by the metal itself. The metal will be observed to glow as a reaction takes place and the result is a vacuum so high that no gas ionization effects can be 80 observed when an electron current is transmitted.

85 Some of the metal appears to be deposited on the electrodes and other parts of the tube partly mechanically and partly by electrostatic attraction. The emissivity of the cathode when at incandescence is greatly increased by the presence of the thorium, or zirconium, deposited thereon so that a given current can be obtained at a much lower 90 temperature. The thorium on the cathode surface remains active in the very good vacuum maintained in the tube by the thorium or zirconium.

95 In Fig. 2 is shown a device filled with rare gas, such as argon, and used particularly as a rectifier, although it may have other uses, for example, as an oscillator. It comprises a bulb or envelop 1, an incandescent cathode 2, and an anode 3, both consisting preferably of tungsten and sealed into the bulb as usual. Before evacuation a side tube 16 may be affixed containing the thorium or zirconium, which later is introduced into the main bulb 1, as indicated at 15. The 100 bulb is first baked out and evacuated in the usual way, dry argon, neon or the like is then admitted at a desired pressure, say, at several centimeters, and the thorium or zirconium is shaken over into the main bulb. 105 110

The side tube 16 is then sealed off at the connection point 17 and is removed. External heating is applied to the material in the bulb until the desired reaction has taken place and the common gaseous impurities in the argon or the like have been removed by combination.

5 The excess of the thorium, or the like, remains in the tube, serving to combine with deleterious gases evolved from the electrodes or tube walls.

In the appended claims thorium is specifically mentioned but I mean thereby to claim also the utilization of equivalents, such, for example, as zirconium, for the purposes of my invention.

What I claim as new and desire to secure by Letters Patent of the United States is:—

1. The method of removing common gases from a device having a cathode of refractory material adapted to be operated at incandescence which consists in heating metallic thorium in said space to its reaction temperature.
- 20 2. The method of producing a high vacuum in a device having a cathode of refractory material adapted to be operated at incandescence containing an attenuated at-

mosphere of common gases which consists in heating thorium therein to the reaction tem- 30 perature.

3. The combination of a sealed envelop, coöperating electrodes, at least one of which is operable at incandescence and a quantity of thorium in a state of rendering it capable of combining with common gases.

4. The combination of an evacuated sealed envelop a cathode therein operable at incandescence, an anode and a quantity of metal of the rare earth group capable of combin- 40 ing with common gases.

5. An X-ray device comprising a sealed, highly evacuated envelop, a refractory cathode, an anode or target, means for heating the cathode to incandescence and a quantity 45 of finely-divided thorium within said envelop.

6. A vacuum device comprising a sealed exhausted envelop and a quantity of thorium within said envelop in a state adapted 50 for combination with residual gas within said envelop.

In witness whereof, I have hereunto set my hand this 5th day of October 1916.

WILLIAM D. COOLIDGE.

It is hereby certified that in Letters Patent No. 1,323,836, granted December 2, 1919, upon the application of William D. Coolidge, of Schenectady, New York, for an improvement in "Methods of Removing Gases and Apparatus Produced Thereby," an error appears in the printed specification requiring correction as follows: Page 2, lines 39-40, claim 4, strike out the words "metal of the rare earth group" and insert the words *thorium in a state rendering it*; and that the said Letters Patent should be read with this correction therein that the same may conform to the record of the case in the Patent Office.

Signed and sealed this 13th day of January, A. D., 1920.

[SEAL.]

M. H. COULSTON,
Acting Commissioner of Patents.

Cl. 250—35.
